US00D794609S

(12) **United States Design Patent** (10) **Patent No.:** **US D794,609 S**
(45) **Date of Patent:** **** Aug. 15, 2017**

(54) **AUDIO CONTROL DEVICE**

(71) Applicant: **KINGSTON DIGITAL, INC.**,
Fountain Valley, CA (US)

(72) Inventors: **Julia Meyer**, Munich (DE); **Manuel Gattinger**, München (DE); **Dominik Schütz**, München (DE); **Christian Stapelbroek**, Wuppertal (DE); **Baron K. Lee**, Fountain Valley, CA (US); **Guan-Hua Tzeng**, Hsinchu (TW); **Yu-kuo Huang**, Hsinchu (TW); **Peter Leekuo Chou**, Fountain Valley, CA (US)

(73) Assignee: **Kingston Digital, Inc.**, Fountain Valley, CA (US)

(**) Term: **15 Years**

(21) Appl. No.: **29/563,300**

(22) Filed: **May 4, 2016**

(30) **Foreign Application Priority Data**

Nov. 4, 2015 (TW) 104306158

(51) **LOC (10) Cl.** **14-03**

(52) **U.S. Cl.**

USPC **D14/218**

(57) **CLAIM**

We claim an ornamental design for an audio control device, as shown and described.

DESCRIPTION

FIG. 1 is a perspective view of an audio control device showing the claimed design;

FIG. 2 is another perspective view of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1;

FIG. 9 is a perspective view showing the audio control device of the claimed design in the first usage state; and, FIG. 10 is a perspective view showing the audio control device of the claimed design in the second usage state.

The broken lines in the drawings represent portions of the audio control device that form no part of the claimed design.

1 Claim, 7 Drawing Sheets
